BY *W. T. von Haller & W. H. Morris Lehman.*

ATTORNEY.

Patented Oct. 5, 1926.

UNITED STATES PATENT OFFICE.

EVERETT E. LUNDBERG, OF DETROIT, MICHIGAN, ASSIGNOR TO BRIGGS MANUFACTURING COMPANY, OF DETROIT, MICHIGAN, A CORPORATION OF MICHIGAN.

WINDOW REGULATOR.

Application filed March 24, 1924. Serial No. 701,502.

This invention relates generally to window operating mechanism and refers more particularly to mechanism designed for raising and lowering vehicle windows and the like.

One of the essential objects of the invention is to provide a window operating mechanism which may be installed as a unit and which will operate easily and steadily for raising and lowering the window.

Another object is to provide a strong and durable mechanism that is simple in construction and that can be manufactured at a comparatively low cost.

15 A further object is to provide a mechanism of this type which in addition to operating the window, is also adapted to retain the same in any position of adjustment.

With the above and other objects in view 20 the invention consists in certain novel features of construction, combinations and arrangement of parts as will be more fully described and particularly pointed out in the appended claims.

25 In the accompanying drawing:—

Figure 1 is a side elevation of a portion of a vehicle body and showing a window control mechanism embodying my invention applied thereto;

29 Figure 2 is a sectional view taken on the line 2—2 of Figure 1;

Figure 3 is a sectional view taken on the line 3—3 of Figure 1.

Referring now to the drawing in which 35 like characters of reference designate corresponding parts throughout the several views, the numeral 1 designates a window that is adapted to be raised or lowered in a frame 2, preferably of a vehicle body. In the upper portion of the frame is an opening 3 that is adapted to be closed by the window when in raised position, while in the lower portion of the frame is a vertical pocket 4 that communicates with the opening 3 and is adapted to receive the window when in lowered position. The window may be of any suitable construction, but is preferably a sashless glass panel that is adapted to slide in suitable guideways 5 secured to the upper 45 right members 6 of the frame.

50 For raising and lowering the window, I preferably provide a supporting arm 7 that is provided at one end with a roller 8 which bears against a channel-shaped strip 9 embracing the lower edge of the panel 1 and

engages a horizontal flange 10 at the lower edge of a bracket 11 secured to the strip 9. The arm 7 is preferably offset as shown at 12 and is preferably pivotally mounted at its other end upon a downward extension 13 of a bracket 14 connecting the upright members of the frame. Journalled in a flanged bushing 15 secured to the bracket 14 is a stub shaft 16 that preferably extends through an elongated opening 17 in an actuating arm 18. This arm is preferably pivoted at its lower end upon a pin 19 secured to the supporting arm 7 adjacent to the pivot 20 and is provided at its opposite edges with parallel flanges 21 having spaced notches 22 therein. An operating crank 23 is preferably non-rotatively mounted on the shaft 16 at the inner end of the bushing 15 and is provided with a suitable handle 24, while a disk 25 has a hub portion 26 non-rotatively mounted on the shaft at the other end thereof and is provided upon one face with a spiral flange 27 adapted to engage the notches 22 in the flanges 21 successively for moving the arm 18 longitudinally to actuate the window supporting arm 7. As shown clearly in Figure 1 of the drawing, the hub portion 26 of the disk is disposed between spaced washers 28 and 29 respectively on the shaft and the arm 18 is guided in its longitudinal movement by the washer 29 and the flange 30 of the bushing 15. Moreover, the inner end 31 of the spiral flange 27 on the disk 25 is disposed opposite to the outer end 32, 90 consequently, the flange 27 is always in engagement with at least two of the notches 22 in the flanges 21 and, as a result, the longitudinal movement of the arm 18 is steady and uniform.

95 In order that the window may be operated with the least amount of muscular effort, I preferably provide a suitable counter-balancing spring 33. One end of this spring is connected to the pin 19, while the other end is preferably provided with a hook 34 for engagement with any of the spaced openings 35 formed in a longitudinally extending embossed portion 36 of the bracket 14.

100 In use, the window 1 may be raised or lowered as desired by operating the crank 23 to rotate the shaft 16 to cause the spiral flange 27 to successively engage the notches 22 in the flanges 21 on the arm 18 so that the 110

latter will be moved longitudinally for actuating the window supporting arm 7.

While it is believed that from the foregoing description, the nature and advantages of the invention will be readily apparent, I desire to have it understood that I do not limit myself to what is herein shown and described, and that such changes may be resorted to when desired as fall 10 within the scope of what is claimed.

What I claim as my invention is:—

1. The combination with a frame and a window movable in the frame, of a bracket secured to the frame, a supporting arm for

15 the window pivoted on the bracket, a longitudinally movable arm pivoted directly to the supporting arm, a shaft extending through the last-mentioned arm, and means carried by the shaft for moving the last-mentioned 20 arm longitudinally to actuate the window supporting arm.

2. The combination with a frame and a window movable in the frame, of a bracket secured to the frame, a supporting arm for

25 the window pivoted on the bracket, a longitudinally movable arm pivoted directly to the supporting arm and having a longitudinally extending slot therein, a rotatable shaft carried by the bracket and extending 30 through the slot in the longitudinally movable arm, means for rotating the shaft, a member carried by the shaft adapted to move the last-mentioned arm longitudinally to actuate the window supporting arm, and 35 a yieldable counterbalancing member connected to the bracket and to the window supporting arm.

3. The combination with a frame and a window movable in the frame, of a bracket secured to the frame, a supporting arm for

40 the window pivoted on the bracket, a longitudinally movable arm pivoted directly to the supporting arm and having a longitudinally extending slot therein, spaced flanges carried by the longitudinally movable arm having aligned recesses spaced longitudinally thereof, a shaft carried by the bracket extending through the slot in the longitudinally 45 movable arm, means for rotating the shaft, and a member carried by the shaft having a spiral flange engageable with the notches in the flanges on the longitudinally

movable arm for moving the latter to actuate the window supporting arm.

4. The combination with a frame and a window movable in the frame, of a bracket secured to the frame, a supporting arm for the window pivoted on the bracket, an arm pivotally connected directly to the arm aforesaid and having spaced flanges provided with aligned notches spaced longitudinally thereof, a rotatable disk having a spiral flange engageable with said notches for moving the last-mentioned arm longitudinally to actuate the window supporting 65 arm, and means for rotating said disk.

5. The combination with a flange and a window movable in the flange, of a bracket secured to the frame, a supporting arm for the window pivoted on the bracket, an actuating arm pivoted directly to the supporting arm and having a slot therein, a bushing secured to the bracket, a shaft journalled in the bushing and extending through the slot in the actuating arm, 75 spaced flanges on the actuating arm having aligned notches spaced longitudinally thereof, a disk on the shaft having a spiral flange engageable with the notches in the flange on the actuating arm for moving the latter to 80 actuate the window supporting arm, and means for rotating the shaft.

6. The combination with a frame and a window movable in the frame, of a bracket secured to the frame, a bushing, spaced 85 washers on the shaft, a supporting arm for the window carried by the bracket, a longitudinally movable arm adapted to actuate the window supporting arm and extending between one of the washers aforesaid and the flange of said bushing, said longitudinally movable arm having a slot therein receiving said shaft, means for rotating the shaft, spaced flanges on the longitudinally 90 movable arm having spaced notches therein, and a member carried by said shaft having a spiral flange engageable with the notches in the flanges on the longitudinally 95 movable arm for moving the latter to actuate the window supporting arm.

In testimony whereof I affix my signature.

EVERETT E. LUNDBERG.
